(57) **CLAIM**

The ornamental design for a display screen or portion thereof with graphic user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphic user interface showing my new design; and, FIG. 2 is a front view of the graphic user interface of FIG. 1, in which a mobile terminal in broken lines is provided to illustrate an example environment.

The broken line showing the mobile terminal are for illustrative purposes only and form no part of the claimed design.

**1 Claim, 2 Drawing Sheets
(2 of 2 Drawing Sheet(s) Filed in Color)**

FIG. 1

FIG. 2
